CLAIM

The ornamental design for a nozzle for a compact tank, as shown and described.

DESCRIPTION

FIG. 1 is a top perspective view of a nozzle for a compact tank showing our new design;

FIG. 2 is a left side view of the nozzle for a compact tank illustrated in FIG. 1;

FIG. 3 is a right side view of the nozzle for a compact tank illustrated in FIG. 1;

FIG. 4 is a front view of the nozzle for a compact tank illustrated in FIG. 1;

FIG. 5 is a back side view of the nozzle for a compact tank illustrated in FIG. 1;

FIG. 6 is a top view of the nozzle for a compact tank illustrated in FIG. 1; and,

FIG. 7 is a bottom view of the nozzle for a compact tank illustrated in FIG. 1.

The broken lines in the drawings illustrate unclaimed portions of the nozzle for a compact tank that form no part of the claimed design.

1 Claim, 4 Drawing Sheets
